(57) CLAIM

I claim the ornamental design for a holder for pots, as shown and described.

DESCRIPTION

FIG. 1 is a side view showing the holder of my design in a use position in conjunction with a conventional plant pot; FIG. 2 is an enlarged view of the holder of my design; FIG. 3 is a bottom view thereof of the holder of my design; FIG. 4 is a front view thereof of the holder of my design; FIG. 5 is a right side view of the holder of my design; FIG. 6 rear view of the holder of my design; and, FIG. 7 is a left side view of the holder of my design. The broken lines showing of a pot is for illustrative purposes only and forms no part of the claimed design.
